Ernest James Smith, Fleet Street, London, England, assignor to The Goss Printing Press Company, Chicago, Ill., a corporation of Illinois

Application September 29, 1934, Serial No. 746,055
In Great Britain January 16, 1934

8 Claims. (Cl. 101—221)

The present invention relates to printing presses and more particularly to a novel and improved late news printing device for use with high speed rotary newspaper presses.

- 5 Objects and advantages of the invention will be set forth in part hereinafter and in part will be obvious herefrom, the same being realized and attained by means of the instrumentalities and combinations pointed out in the appended claims.
- 10 The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is an end elevation of the present illustrative embodiment of the invention;

Figure 2 is a side elevation of the mechanism shown in Figure 1, with certain parts broken away;

Figure 3 is a section taken on the line 3—3 of Figure 2; and

Figure 4 is a section taken on the line 4—4 of Figure 3.

The present invention has for its object the provision of a novel and improved printing press provided with late news printing mechanism by which the late news matter may be changed without stopping the running of the web or the production of newspapers. Another object is the provision of a high speed rotary newspaper printing press having two late news printing devices adapted for alternative operation and which may be operated simultaneously to print in multicolor. Still another object of the invention is the provision of a printing press having two alternatively and simultaneously operable late news printing devices driven from a common source of power and adapted to be driven only in registering relation with another part of the press, such as the printing cylinders of conventional newspaper printing units.

In accordance with the illustrative embodiment of the present invention, a web of paper, which may be previously printed with the main body of the text by one of the conventional units, is led between a pair of rotary printing couples adapted to print late news upon the proper portion of the web. Means are provided for driving one or the other or both of the printing couples and for moving the silenced impression cylinder away from its printing cylinder and for prevent-

ing driving of the silenced printing and impression cylinders. In the illustrative embodiment, differential gearing is driven from the main press driving means and is connected to the impression and printing cylinders of the two late news printing couples, and means are provided for alternatively transmitting power to either or both of the differentials, these means also serving to move the impression cylinder of the corresponding couple into or out of printing contact with its printing cylinder. Means are also provided for stopping the differential in a predetermined position whenever it is to transmit power so that accurate registration of the corresponding printing couple is always assured. Means are also provided for simultaneously driving both of the late news printing couples and for moving both impression cylinders into printing contact whereby separate impressions in different colors may be made by the late news printing couples.

It will be understood that the foregoing general description, and the following detailed description as well, are exemplary and explanatory of the invention, but are not restrictive thereof.

Referring now in detail to the illustrative embodiment of the invention as shown in the drawings, there are provided two late news printing couples comprising the printing cylinders 10 and 11 and their cooperating impression cylinders 12 and 13, and the web of paper 14 is passed first between one couple, over the guide rollers 15, and then between the other couple, being printed by either one or both of the two printing couples. Suitable inking means may be provided for supplying ink to the form inking rollers 16.

Printing and impression cylinders 10, 11, 12 and 13 are suitably rotatably journaled in the side frames 18 and 19, and the printing cylinders are adapted to be driven from their impression cylinders by means of the gears 20 fixed to the ends of the cylinder shafts.

Means are provided for driving one or the other, or both, of the printing couples and for this purpose bevel gear 22 is fixed to the drive shaft 23 which is driven from suitable driving means, not shown, such as the usual main horizontal drive shaft of the press. Gear 22 meshes with a similar bevel gear 24 fixed to one end of shaft 25 which is rotatably journaled in the side frames 18 and 19 and is positioned between the two printing couples. Shaft 25 carries near either side frame 18 and 19 a differential through which power may be transmitted from the shaft to one or the other or both of the printing couples. As embodied, each differential comprises a bevel

gear 27 keyed to the shaft 25 and meshing with the revolute pinions 28 mounted on the shafts 29 which are carried by sleeve 30, freely journaled on the shaft, and the differential drum 31. Pinions 28 in turn mesh with the bevel gear 32 which carries near one end a spur gear 33 keyed to the gear 32. End plates 34 cooperate with the drum 31 and gears 27 and 32 to substantially enclose the gears comprising the differential. Gear 33 meshes with a gear 35 keyed to the corresponding impression cylinder shaft and serving to drive the impression cylinder whenever the differential drum 31 is held against rotation. Means are also provided permitting the impression cylinders to be moved into and out of printing contact with their respective plate cylinders, and as embodied, the impression cylinders are mounted at either end in eccentricities carried in the frame and which may be rotated to space the impression cylinders from the plate cylinders or to move the impression cylinders into printing contact. Eccentricities 36 are provided for the impression cylinder 12 and eccentricities 37 are provided for the impression cylinder 13. The eccentricities 36, one at each end of the impression cylinder 12, are each provided with a toothed segment 38 meshing with pinions 39 carried by shaft 40 which is rotatably journaled in the side frames 18 and 19 and is connected to a handle 41 by which the shaft and eccentricities 36 may be rotated. Suitable means, such as the notched arcuate bar 42, are provided for holding the handle 41 and the eccentricities 36 in either printing or non-printing position. Eccentricities 37 are similarly provided with toothed segments 43 cooperating with pinions 44 mounted on shaft 45 and movable by handle 46.

Means are also provided for individually controlling the application of power to the impression cylinders coincidentally with the movement of the impression cylinders to or from printing position, so that power is always supplied to the impression cylinder when it is in printing position. For this purpose, braking means are provided cooperating with the differential drum 31, and adapted to be applied only when the impression cylinder is in printing position with respect to its plate cylinder. As embodied, a brake band 48 encircles the differential drum 31 near one end thereof and is supported and actuated by flange 49 mounted on shaft 40. At one end the brake band 48 is provided with a lug 50 pivotally supported on pin 51 carried by the flange 49, while at its other end the brake band is connected with the flange-supported pin 52 by means of a turn buckle 53. These parts are so arranged and positioned that the brake is applied to stop drum 31 and thereby transmit power to the cylinder 12 as handle 41 is moved to impression position. Although the brake band 48 may be actuated directly from the shaft 40, it is preferably resiliently connected thereto, and for this purpose a spring 55 is coiled about shaft 40 and has its ends connected to flange 49 and a collar 56 which is pinned to shaft 40, thereby resiliently rotating the flange 49 as the shaft 40 is rotated.

In order to secure accurate registration of the late news printing couple with the other couples of the press operating on the web, means are provided for positively stopping rotation of the differential drum 31 in a definite position, thereby insuring that the printing cylinder 10 is in exact registration with the other printing cylinders 12 of the press. As embodied, a stop is provided

coacting with the brake band 48 to stop the differential drum 31 in a definite position, this stop being brought into operation by movement of the lever 41 which serves to apply the brake band 48. The stop comprises a three-armed lever 60 pivotally mounted on a stub 61 projecting inwardly from the side frame 18. One arm 62 extends towards the differential drum 31, and at its forward end is adapted to engage in recess 63 formed in the cylindrical surface of drum 31, and when so engaged prevents rotation of the drum in one direction. Means are provided for resiliently pressing the stop arm 62 against the drum and into the recess 63 and for this purpose a spring 64 is connected between the side frame 18 and the arm 65 of lever 60. Means are also provided releasing the stop 62 whenever the brake 48 is released and for this purpose the arm 66 of lever 60 is provided with a cam roller 67 adapted to bear against the peripheral surface of cam 68 fixed to the shaft 40, this cam being so shaped and positioned that the stop is fully withdrawn when the brake is released, and is moved to operative position by application of the brake.

Means are also provided for controlling the application of power to the cylinders 13 and 14, and for this purpose the differential, brake, impression control and positive stop for the differential drum are substantially duplicated, and as these parts are substantial duplicates of those described immediately above, this description will not be repeated.

In the operation of the embodiment described, the cylinder 10 is plated in the usual way with semi-cylindrical stereotype plates which are secured to the surface of the cylinder by means of suitable clamping devices (not shown). The web of paper 14, which has already been printed with the major portion of the reading matter or is later to be so printed, passes between the cylinders 11 and 13, out of contact with each other, passes over the guide rollers 15 and is then led between the printing cylinder 10 and its cooperating impression cylinder 12, eccentric 36 being so positioned by its operating member 41 that these cylinders are maintained in printing contact. Cylinders 10 and 12 are driven from the vertical drive shaft 23 driving bevel gears 22 and 24, shaft 25, differential gear 27, differential pinions 28, differential gear 32, spur gears 33 and 35, gear 20 on the shaft of cylinder 12 and finally gear 20 on the shaft of cylinder 10. Power is transmitted through the differential gearing inasmuch as the differential drum 31 and the pinion shafts 29 are held against movement by brake bands 48 and stop arm 62. Cylinders 10 and 12 are thus driven at exactly the speed of the other couples of the press operating on the web 14, and in register therewith.

When it is desired to change the late news, it is necessary to provide a new stereotype plate or plates which are secured to the cylinder 11 the same way as the plates are secured to the cylinder 10. After these plates have been clamped on the cylinder, the operator moves handle 41 to inoperative position, and simultaneously therewith moves the handle 46 to operative position. This movement of the handles 41 and 46 moves the cylinder 12 away from its plate cylinder 10, at the same time allowing the corresponding differential to idle, and cylinder 13 is moved into printing contact with its plate cylinder 11 while the corresponding brake drum 48 and stop lever 62 are moved into position, thereby applying the power

to the cylinders 11 and 13 and rotating them in register with the other couples of the press as soon as this stop 62 has engaged in the recess 63. In this way, the printing of the late news may be transferred from cylinder 10 to cylinder 11 without stopping or slowing down the running of the press.

When it is desired to print in multicolor, the cylinders 16 and 11 are plated with the proper stereotype plates, and both handles 41 and 46 are moved to impression position, thereby rotating both couples through the two differentials. For multicolor printing, the web 14 may be previously or subsequently printed in one or more colors by the other couples of the press, and in this way it is possible to produce a web printed in four colors or in three colors and perfected in one color by the use of the illustrated embodiment of the present invention in connection with a single newspaper unit of conventional design.

The invention in its broader aspects is not limited to the specific mechanisms shown and described but departures may be made therefrom within the scope of the accompanying claims without departing from the principles of the invention and without sacrificing its chief advantages.

What I claim is:—

1. In a late news printing mechanism, in combination, an impression cylinder and a plate cylinder, driving means therefor including a differential, means for throwing on and off the impression, means for controlling the differential, means cooperating with the differential to keep said cylinders in registry with the cylinders of the press and a common manual means for controlling the last three means.

2. In a late news printing mechanism, in combination, an impression cylinder and a plate cylinder, means for throwing on and off the impression, driving means for said cylinders, a manually operated mechanism for concurrently throwing on and off the impression concurrently with the starting and stopping of said driving means, and means for maintaining said cylinders in registry with the cylinders of the press.

3. In a late news printing mechanism, in combination, an impression cylinder and a plate cylinder, driving means therefor including a differential, means for throwing on and off the impression, means for controlling the differential, means cooperating with the differential to keep said cylinders in registry with the cylinders of the press, and a manually operated mechanism for throwing on and off the impression concurrently with the starting and stopping of the differential and controlling said registry means.

4. In a late news printing mechanism, in combination, a plurality of plate cylinders, means for throwing on and off the impression for each of said cylinders, driving means for each of said cylinders, means cooperating with each of said driving means to start a corresponding impression cylinder in registry with the cylinders of the press, means for starting and stopping the drive for one of said cylinders, and means for starting and stopping the drive for another of said cylinders and a plurality of manually operated means, each of said manually operated means controlling all of said means acting on each plate cylinder, said manually operated means being actuatable independently of each other.

5. In a late news printing mechanism, in combination, a plurality of plate cylinders, means for throwing on and off the impression for each of said cylinders, driving means for each of said cylinders, means cooperating with each of said driving means to start a corresponding impression cylinder in registry with the cylinders of the press, means for starting and stopping the drive for one of said cylinders, and means for starting and stopping the drive for another of said cylinders and a plurality of manually operated means, each of said manually operated means controlling all of said means acting on each plate cylinder, said manually operated means being actuatable independently of each other, and both said manually operated means being actuatable from a single station.

6. A rotary printing press including in combination a pair of printing couples for alternatively or concurrently printing on a web, each couple having a plate and an impression cylinder, a common drive shaft, a differential gear between each couple and the drive shaft, optionally operable means for rendering each differential operative to transmit power from the drive shaft to its respective couple, individual means for spacing the cylinders of each couple in non-printing position and a pair of means, each common to one of the optionally operable means and the corresponding spacing means, for first controlling the differential and then the spacing means to drive the printing couple prior to its movement to printing position, said pair of means being individually or concurrently operable.

7. A rotary printing press including in combination a pair of printing couples for alternatively or concurrently printing on a web, each couple comprising a plate and an impression cylinder, means for moving the impression cylinder of each couple into and out of printing position relatively to its plate cylinder, and means for driving each couple, said driving means including a drive shaft, two sets of differential gearing driven by said shaft, one for each couple, brake means operating on each differential to cause it to transmit power from said shaft to its respective couple and a common means for operating each of said brake means and then the respective impression cylinder moving means whereby an impression cylinder is first driven and then placed in printing position.

8. A rotary printing press including in combination a pair of printing couples for alternatively or concurrently printing on a web, each couple comprising a plate and an impression cylinder, means for moving the impression cylinder of each couple into and out of printing position relatively to its plate cylinder, and means for driving each couple, said driving means including a drive shaft, two sets of differential gearing driven by said shaft, one for each couple, brake means operating on each differential to cause it to transmit power from said shaft to its respective couple, a common means for operating each of said brake means and then the respective impression cylinder moving means whereby an impression cylinder is first driven and then placed in printing position, and means for locking each differential in a definite position to register its respective printing cylinder.
